GARMENT

Filed Sept. 27, 1928

Inventor

R. A. Neal

By *Watson E. Coleman*
Attorney

UNITED STATES PATENT OFFICE

ROBERT AUGUST NEAL, OF CAPE GIRARDEAU, MISSOURI

GARMENT

Application filed September 27, 1928. Serial No. 308,803.

This invention relates to the class of garments and pertains particularly to cover all types of garments.

In the one piece cover all types of garments at present in use, it has been found that due to the drag upon the back of the garment when the wearer thereof stoops or leans over, considerable strain is placed upon the back of the neck of the garment resulting in the choking of the wearer. The primary object of this invention is to overcome this choking action of the garment and, while the following description will be confined to a one piece overall garment it is, of course, to be understood that the invention may be readily applied to the other garments such as shirts and the like.

The present invention overcomes the above described difficulties by laying a pleat across the top edge of the back of the garment, between the shoulder seams thereof securing this pleat at each end to the seams. The result of forming the upper portion of the garment in this manner is to place the strain or drag upon the shoulders, the pleat opening out when a pull is applied to the central portion of the back thereof, thus temporarily lengthening the back and preventing any drag upon the wearer's neck.

A further object of this invention is to overcome the above described difficulty economically and in such a manner that the manufacturing operation of the garment will not be made more difficult.

The invention will be best understood from a consideration of the following detailed description taken in connection with the accompanying drawings forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is an elevational view of the upper back portion of a garment constructed in accordance with this invention;

Figure 2 is a sectional view taken on the line 2—2 of Figure 1.

Referring to the drawing in detail, the numeral 1 indicates the back of a garment, for example a one piece overall suit to the upper or shoulder edges of which the breast pieces are secured forming the seams 2.

In the usual construction of a garment of this type, the central top edge of the back is secured directly to the lower edge of the collar 3. However, in the present invention, the top central edge of the back is folded back upon itself as indicated at 4 and then again folded upwardly as indicated at 5 to form the transverse pleat indicated as a whole by the numeral 6.

The ends of the pleat 6 are secured by the stitching which forms the seams 2, while the top edge thereof is secured between the two plies of material which forms the collar 3 as indicated at 7.

From the foregoing description, it will be readily understood that in a garment constructed in the manner described when the lower portion of the back is held from being drawn upwardly as is the case in a one piece garment, when the wearer thereof leans over or stoops, a considerable drag will be placed upon the back which in the ordinary types of garments results in the pulling of the collar 80 against the throat of the wearer. In the present structure the fold or pleat 6 will open out to a sufficient extent to prevent any un- 80 comfortableness to the wearer.

While the present description has been confined to a one piece overall garment, it is, of course, to be understood that the present invention may be advantageously applied to other articles of clothing such as shirts and the like.

Having thus described my invention what I claim is:—

1. An article of apparel designed to encase the torso and having a neck, means for relieving drag upon said neck comprising an expandable fold formed in the back portion of the garment across the top thereof adjacent the neck, said fold having each end secured to the garment, on opposite sides of the neck.

2. In an article of apparel designed to encase the torso and having a neck and shoulder seams, means for relieving drag upon said neck, comprising an expansible fold formed in the back portion of the garment across the top thereof adjacent the neck, said fold having each end secured under a shoulder seam of the garment.
- 5
3. In an article of apparel having a neck opening, means for relieving drag on the edge of said neck opening, comprising an expansible fold formed of the material of the article and extending transversely of the neck at the back thereof, one longitudinal edge of said fold forming a part of the neck opening.
